UNITED STATES PATENT OFFICE.

J. WILLIAM BONSACK, OF BONSACK'S, VIRGINIA.

COMB-PLATE FOR DOFFER-COMBS OF CARDING-ENGINES.

SPECIFICATION forming part of Letters Patent No. 363,199, dated May 17, 1887.

Application filed February 21, 1887. Serial No. 228,381. (No model.)

To all whom it may concern:

Be it known that I, J. WILLIAM BONSACK, of Bonsack's, in the county of Roanoke and State of Virginia, have invented certain new 5 and useful Improvements in Comb-Plates for Doffer-Combs of Carding-Engines; and I do hereby declare the following to be a full, clear, and exact description of the same, reference being had to the accompanying drawings, forming a part of this specification, and to the figures and letters of reference marked thereon.

My invention has for its object to improve the construction of the doffer knife or comb employed on carding-machines for the purpose 15 of removing the fleece from the carding-cylinder direct, or from the doffer-cylinder sometimes employed, whereby there will be no liability of tearing or cutting the fiber of the cotton or wool, but the same will be delivered 20 intact at the side where the "sliver" is formed and finds its exit through the perforations and is delivered to the containing-cans; and it further consists in a certain improved construction which will be hereinafter described, and 25 pointed out in the claims at the end of this specification.

In the drawings, Figure 1 is a perspective view through a portion of a carding-engine of 30 approved construction; Fig. 2, a perspective view of a portion of a doffer-comb constructed in accordance with my invention and of the trumpet or guide for the sliver.

Similar letters of reference in the several figures indicate the same parts.

Heretofore the doffer-combs employed in carding-machines have been constructed with a number of serrations on their lower or operating edges and adapted to be vibrated very rapidly in proximity to the carding-cylinder 40 or to a "doffer-cylinder" that operates to remove the fleece from the same primarily. These combs are preferably placed at a slight angle to the axis of the cylinder against which they operate, so that the fleece is more readily 45 guided to the perforation at the side of the machine, from where it issues in the form of the sliver.

As stated, the teeth of the combs are formed in the shape of equilateral triangles—that is, 50 with the two sides having equal angles—but the objection to this is that the fleece when

pulled to one side is drawn across the ends and sides of the teeth and the fiber is cut or torn by the sharp points, producing, of course, a poor quality of thread or yarn, liable to break 55 very readily, and it is this portion particularly of the machine that my invention is designed to improve by making one side of the teeth of the doffer-comb more inclined than the other, the shorter side of the teeth being presented to the side of the machine where the sliver is formed, so that the fleece will be drawn over the long side of the teeth and will not be torn or cut by the sharp ends of the same as in constructions heretofore. 60

A in the drawings indicates the main carding-cylinder, and B the doffer-comb, reciprocated rapidly by any suitable device in proximity to the surface of the same for the purpose of removing the fleece therefrom, as will 65 be readily understood by one skilled in the art.

At the side of the machine is provided a perforated trumpet, C, through which the fleece is drawn by any suitable mechanism to 70 form the sliver adapted to be delivered to the can in which it is usually placed, or to another suitable machine adapted to operate upon it in any suitable manner.

In Fig. 2 is shown a portion of the doffer-comb B in its operative position relative to the sliver-forming trumpet or cone, and, as stated, provided with the teeth E E, having the side b inclined to any desired angle—say thirty-five degrees, or any other found most convenient— 80 and the side e inclined at a much less angle, as indicated. The inclined side of the teeth is, as stated, placed away from the perforation, by which the sliver is slightly condensed, as usual, and the fleece is drawn over this, thus obviating 85 the cutting produced by the ordinary combs.

The comb, instead of being employed to remove the fleece directly from the carding-cylinder, can as well be employed to remove it 90 from a doffer-cylinder placed between it and the carding-cylinder, and can be operated either upon the upper or lower side of the same, as will be readily understood.

Having thus described my invention, what I 95 claim as new is—

1. The herein-described doffer-comb having

the teeth, one side of which has a greater inclination than the other, substantially as described.

2. In a carding-machine, the combination, 5 with the cylinder on which the fleece is carried and the sliver-forming device, of a doffer-comb having the teeth, one side of which has

a greater inclination than the other, said less inclined side being arranged toward the sliver-forming device, substantially as described.

J. WILLIAM BONSACK.
